CLAIM

The ornamental design for a PDU power outlet, as shown
and described.

DESCRIPTION

FIG. 1 is a front view of a new PDU power outlet;
FIG. 2 is a detail view of the encircled portion 2 on FIG. 1;
FIG. 3 is a detail view of the encircled portion 3 on FIG. 1;
FIG. 4 is a rear view of the new PDU power outlet;
FIG. 5 is a left view of the new PDU power outlet;
FIG. 6 is a right view of the new PDU power outlet;
FIG. 7 is a top view of the new PDU power outlet;
FIG. 8 is a bottom view of the new PDU power outlet; and,
FIG. 9 is a perspective view of the new PDU power outlet.
The evenly spaced broken lines depict environmental sub-
ject matter and form no part of the claimed design. The
line-dot-line broken lines that encircle portions of FIG. 1 and
that surround the detail views on FIGS. 2 and 3 respectively
form no part of the claimed design.

The line-dot-line broken lines of FIGS. 5, 6, and 9 depict
boundaries of the claim and form no part of the claimed
design.
